UNITED STATES PATENT OFFICE.

LOUIS WEIGEL, OF HELENA, MONTANA.

LABEL-HOLDER.

SPECIFICATION forming part of Letters Patent No. 723,093, dated March 17, 1903.

Application filed July 26, 1902. Serial No. 117,118. (No model.)

To all whom it may concern:

Be it known that I, LOUIS WEIGEL, a citizen of the United States of America, residing at Helena, in the county of Lewis and Clarke 5 and State of Montana, have invented certain new and useful Improvements in Label-Holders, of which the following is such a full, clear, and exact description as will enable others skilled in the art to which it appertains to 10 make and use the same, reference being had to the accompanying drawings, forming a part hereof.

This invention has special reference to devices of the type shown in the patent issued 15 to me August 14, 1900, No. 655,843, and it aims to produce a device of a cheaper and simpler construction.

With this object in view the invention consists in certain novel features, hereinafter 20 first fully described and then particularly pointed out in the claim.

In the accompanying drawings, which fully illustrate the invention, Figure 1 is a front elevation of the device. Fig. 2 is a horizontal 25 section of the same, and Fig. 3 is a vertical section thereof.

In carrying out my present invention I employ a strip of any suitable material, preferably sheet metal, (designated by the letter A 30 in the drawings,) and through the same, near the ends thereof, insert fasteners B, as shown, which are adapted to be inserted through the hat-box and then bent against the inner face of the box to secure the device thereto, as will 35 be readily understood on reference to Fig. 2 of the drawings. The lower edge of the strip is bent horizontally backward along its entire length to present the supporting-flange C, and at intervals along its length the strip 40 is provided with open-ended pockets, formed by striking back portions of its body, as shown at D and as will be readily understood on reference to Fig. 2. The tags or registry-cards E are inserted through these pockets 45 and are supported therein by the flange C, so that the matter on their faces may be readily seen through the open fronts of the pockets. The supporting-flange C is large enough to support a style and price card F in rear of 50 the pockets and between the same and the hat-box, as indicated in Figs. 1 and 2.

The holder is secured to the box by insert-

ing the fasteners through the wall of the same, as before described, and the tags or cards designating the sizes of the hats contained in 55 the box are then inserted into the pockets and supported by resting on the flange C, as clearly shown in Fig. 3. When a hat is sold from the box, the tag denoting the size of the same is slipped upward from the pocket, and 60 the empty or blank pocket at once shows that the hat has been removed. Should the style and price card not be used, there is nothing above the size-tags to mar the appearance of 65 the box, and at the same time the card may be easily placed in position if it is wanted.

The device is extremely simple and may be used indefinitely, as it may be removed from one box and applied to another in a few seconds and there are no costly fastening devices to be lost. The tags may be readily slipped into or out of the pockets and constitute a visual record of the stock at all times. When the tags are within the pockets, their 75 edges are covered by the body of the holder, which serves to hold them against any tendency to drop forward. There are no lips projecting forward from the device which are liable to catch in the clothing of the persons handling the box in the sale of the goods, and 80 consequently there is no liability of the tags being accidentally drawn from the pockets and lost.

Having thus described my invention, what I claim, and desire to secure by Letters Patent, is—

The improved label-holder for hat-boxes herein described and shown consisting of a metallic strip provided with fastening means at its ends, having portions of its body struck 90 back to form integral vertical open-ended pockets adapted to receive size-indicating cards, and having its lower edge bent horizontally backward to form a flange for supporting said cards, said flange projecting rearward beyond the said pockets to support a descriptive card in rear of the same.

In testimony whereof I have signed this specification in the presence of two subscribing witnesses.

LOUIS WEIGEL.
